DRAG HOOK

Filed May 31, 1949

UNITED STATES PATENT OFFICE

2,579,864

DRAG HOOK

Kenneth M. Rooker, Des Moines, Iowa

Application May 31, 1949, Serial No. 96,281

3 Claims. (Cl. 294—66)

1

The principal object of my invention is to provide a drag hook designed for facilitating and expediting the discovery and recovery of submerged objects such as that of a human body or the like.

A further object of this invention is to provide a means for discovering and recovering submerged objects which means can be easily and quickly submerged and surfaced.

A still further object of this invention is to provide a drag hook designed for discovering submerged objects that can be easily maneuvered laterally along the bottom of a body of water and thus covering more area in any given time and therefore facilitating the discovery of the object sought.

A still further object of this invention is to provide a means for recovering submerged objects that is easily adjustable so as to be capable of securing a hold on said object whether it be resting on the bottom of a body of water or partially embedded therein.

A still further object of this invention is to provide a means for discovering and recovering submerged objects that can be operated either from the surface of a body of water or at a distance therefrom.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of this device, but showing only the connecting portion of the handle member.

Fig. 2 is a side view of this device taken from line 2—2 of Fig. 1.

Fig. 3 is a side view of the sectional handle for this device shown in a position in extension of Fig. 1 with the lower dotted lines showing adjustable position of the main portion of this device.

Fig. 4 is a cross-sectional view of the handle of this device taken on line 4—4 of Fig. 3.

Fig. 5 is an enlarged cross-longitudinal view of a section joint of the handle of this device taken on line 5—5 of Fig. 4.

The discovery and recovery of submerged objects and particularly dead bodies is usually attempted by means of grappling hooks. These hooks can be dragged along the bottom but cannot be laterally controlled to traverse an under

2

area. Also such hooks will snare any object such as logs or the like causing confusion and delay in completing the search. These objections I have overcome as will appear from the description of my invention.

Referring to the drawings I have used the numeral 10 to designate a flat elongated metal base member having its corners rounded.

The sides of the front portion of the base member 10 are slightly tapered toward, but not to, the center thereof to form the reduced forward end 11, and this entire tapered portion is curved upwardly, as shown in Fig. 2.

The numeral 12 designates an elongated bar member having a short portion 13 thereof at the front twisted to the vertical so that the wide side of the front end portion is in a position transverse to the wide side of the bar member 12, as shown in Fig. 1. A hole is provided through the narrow width of the front portion 13 for use as hereinafter described. The forward portion of the bar member 12 and to the rear of the portion 13 thereof is provided with a plurality of holes 14 arranged in line along its longitudinal axis.

The numeral 15 designates a hook member formed from a single piece of metal rod. The top of the hook rod is bent to form an eye 16, and the rear portion is curved downwardly in a U-shaped hook and has a barbed point similar in appearance to an ordinary fish hook, as shown in Fig. 2.

The hook 15 is detachably secured to the upper underside of the bar member 12 at any one of the holes 14 desired by means of a bolt 17 passing through one of the holes 14 and the eye 16 in the hook 15, as shown in Fig. 2.

The rear end of the bar member 12 is welded to the longitudinal center of the upper surface of the base member 10 at approximately the base of the upwardly curved portion thereof and is also welded to the base member 10 at the point where it rests upon the top edge of the front center portion 11, as shown in Fig. 2.

The numeral 18 designates a bearing member that is detachably vertically hingeably secured to the portion 13 of the bar member 12 by means of the bolt 19, as shown in Fig. 1 and Fig. 3. To the free upper end of the bearing member 18 I have welded a section of metal pipe 20 to serve as the portion of a handle and in Fig. 3 I show this handle with additional pipe sections detachably secured together by couplings 21 provided with studs 22 for facilitating the tightening or loosening thereof. On each section of these

handle pipes 20 I provide an eye 23 by means of which the several handle extensions can be joined to a single safety cord, if desired. While I have used a sectional pipe arrangement for the handle in my drawings, this device may be used by a longitudinally flexible cable or the like secured to the member 13.

This invention is designed to facilitate and expedite the discovery and recovery of submerged objects and while recovering human bodies was one of the main purposes motivating the creation of this device, it can be used for recovering a multitude of other objects by a variation in its size.

This device may be used either from a bridge or the shore line but it is particularly of value when operated from a boat. The device is placed in the water with the bottom of the base member down and will thereupon sink to the bottom by its own weight. Adjustment of the bearing member 18 on the portion 13 will adjustably lower or raise the hook relative to the normal operation of the device as a whole. Further adjustment of the hook position is possible by arranging it on the bar member in any one of the holes 14 therein for any desired position.

This device is pulled through the water by means of the handle, cable or the like with the wide surface of the base member normally riding the bottom of the river or lake. A twist of the handle clockwise will cause the base portion to slide laterally to the left along the bottom and by twisting the handle counterclockwise the device will move to the right. This results from the water acting upon the turned base portion as in the case of a rudder. By this lateral controllable movement a wide area can be quickly covered.

The flat "beaver tail" base curved upwardly at its forward end, is the heart of the device. It gives complete control of the device to the operator at all times. Besides lateral control, it may be turned upside down, and if the operator is in a moving boat, the action of the water will cause the complete device to raise from the bottom of the water area to the surface of the water. Under normal conditions, however, it will "sled" on the water area bottom, riding over boulders, logs and the uneven water bottom, thereby successfully raising the hook over such unwanted obstructions. This characteristic of riding over unwanted obstructions is due to the upwardly curved forward end portion of the base 10. The only part of the device capable of snagging on an object is the hook 15 and its position is above and forward of the portion 10 of the base.

By adjusting the angle of the bearing 18 to the portion 13, or by adjusting the hook along the length of the bar 12, the hook may be adjustably set relative to the rest of the device to the size of the object sought. Smaller objects in the

water and not wanted would not be engaged by the hook. If a hook should become damaged it is a simple matter to replace it with a new one.

Preferably, the base portion should be made of heavy material such as iron so that its weight will be such that it will follow over the bottom of the water area even though the trolling boat is moving relatively fast. Once the desired object is hooked it may be easily and quickly pulled up to and into the boat by my device.

By the hook being reasonably protected against unwanted objects, a wide water area may be quickly and easily searched. This is highly desirable in the recovery of bodies for if they are not recovered with dispatch, they may well be permanently lost. This is especially true in rivers or like where the water is in motion.

Some changes may be made in the construction and arrangement of my drag hook without departing from the real spirit and purpose of my invention, and it is my intention to cover by my claims, any modified forms of structure or use of mechanical equivalents which may be reasonably included within their scope.

25 I claim:

1. In a drag hook, an elongated flat base member curved upwardly at one end, a bar member secured to that end of said base member that is curved upwardly and a hook member detachably and longitudinally adjustable on said bar member, and a manual control means secured to said bar member.

2. In a drag hook, a flat base member, an elongated bar member secured to said base member, a bearing member vertically adjustably secured to said elongated bar member, a hook member detachably secured to said elongated bar member, and longitudinally adjustable thereon and a handle member secured to said bearing member.

3. In a drag hook, an elongated flat base member, a bar member secured to said base member, a hook member detachably and longitudinally adjustable on said bar member, and a manual control means secured to said bar member.

45 KENNETH M. ROOKER.
